UNITED STATES PATENT OFFICE.

JOSEPH GOULDBOURN, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR INSERTING NAILS IN HEELS.

1,002,836.

Specification of Letters Patent. Patented Sept. 12, 1911.

Application filed October 13, 1906. Serial No. 338,848.

To all whom it may concern:

Be it known that I, JOSEPH GOULDBOURN, a subject of the King of England, residing at Leicester, in the county of Leicester, England, have invented certain Improvements in Machines for Inserting Nails in Heels, of which the following description, in connection with the accompanying drawings, is a specification, like reference characters on the drawings indicating like parts in the several figures.

This invention relates to machines for inserting nails in heels, and while many features of the invention may be used advantageously in other types of machines, the invention is herein shown and described as embodied in a machine for attaching heels to boots or shoes.

An object of the present invention is to improve the construction of machines of this class so that they may be operated at a higher rate of speed than has before been possible.

A further object of the invention is the improvement of such machines so that they may be more readily adjusted to operate upon different classes or sizes of work than has been possible with machines as heretofore constructed.

I have shown the invention herein embodied in a machine for attaching heels to shoes by nails driven from the inside of the shoe. It will be understood, however, that features of the invention are capable of use as well in connection with machines for driving heel-attaching nails from without a shoe.

A novel feature of the present invention consists in the provision in a heel-attaching machine of a die-block provided with driver passages; a movable nail-transferrer arranged to be reciprocated to supply successive sets of nails to the die-block for attaching successive heels, and a plurality of movable heel-holders arranged to be brought successively into attaching position by the successive reciprocations of the nail-transferrer.

Another feature of the invention consists in novel means for presenting heel-blanks for the operation of the machine. In the preferred embodiment of the invention this

means comprises a rotatable carrier for heel holders having radially disposed arms extending outwardly from a central hub, the arms being spaced substantially 120° apart and carrying on their outer ends the heel holders which are moved from receiving position to an intermediate position and then to nailing position by an intermittent rotation of the carrier.

In this connection the invention contemplates also a novel mechanism for effecting the required rotation of the carrier. It has been found advantageous to divide each rotation of 120° into two movements. To this end coöperating cams may be arranged to rotate said carrier after the nailing operation for any desired portion of 120° , then to maintain the carrier stationary and finally to rotate the carrier for the remaining portion of the 120° necessary to move a holder into nailing position.

Another feature of the invention consists in the provision of a pressure-plate for engaging a heel, means for adjustably sustaining said plate in a position inclined longitudinally of the shoe and a heel-holder for sustaining a heel in line with the heel seat of the shoe arranged for adjustment simultaneously with said pressure-plate. In the construction shown, the heel-holder is carried by the pressure-plate so that the relation of the holder to the face of the pressure-plate is not changed by adjustment of said pressure-plate. The pressure-plate is engaged by the tread face of the heel and is adjustable about an axis that is at or near the level of the heel seat of a shoe. Such adjustment permits driving the attaching nails at the desired inclination to the tread face of the heel.

The heels are held upon the heel-holders by gages arranged to engage the breast and rear of the heel and these gages are arranged for adjustment to accommodate heels of different sizes. To facilitate the adjustment of the several sets of gages the present invention also contemplates the employment of means providing connection between said sets of gages, whereby they may be adjusted simultaneously. As will be obvious, the arrangement may be such that the position of all the breast gages, or all the rear gages, or

all breast gages and rear gages may be simultaneously adjusted. In order that the centers of heels of different sizes may occupy the same position on the heel-holder, the construction herein illustrated is such that the breast and rear gages may be simultaneously adjusted in opposite directions upon the respective holders.

In the machine herein disclosed the die-block will not always lie at precisely the same elevation in its nail-receiving position. To avoid the necessity of vertically adjusting the nail-transferrer for every alteration in the position of the die-block the present invention includes a provision of means whereby the transferrer is mechanically moved vertically into close relation to the face of the die-block in its movement into nail-delivering position, and is restored to its initial position when returned to nail-receiving position. The construction shown is such that the transferrer is brought yieldingly into contact with the face of the die-block so that variations in position of the latter are mechanically provided for. This construction as will be apparent is particularly advantageous when the face of the die-block has a somewhat convex configuration, the face of the transferrer being made concave to fit the die-block. In the embodiment of the invention selected for purposes of illustration the die-block is arranged to enter a shoe and to support the shoe upon it. The die-block is arranged for movement into and out of attaching position to facilitate arranging a shoe in position upon it. The nails are supplied to the die-block while the latter is in its inoperative position. To insure that the die-block will be in the precise position required to cause the nail passages of the transferrer to be in line with the nail cavities of the die-block the present invention includes an arrangement whereby the nail-transferrer in its movement into nail-delivering position mechanically adjusts the die-block into proper position.

Other features of the invention will be hereinafter described and defined in the claims.

In the drawings which illustrate one embodiment of the invention, Figure 1 shows a side elevation of the upper portion of a heel-attaching machine embodying the invention; Fig. 2 is a view in front elevation of the parts shown in Fig. 1; Fig. 3 is a view in horizontal section of the machine; Fig. 4 is a view similar to Fig. 3, illustrating a different position of the parts; Fig. 5 is a detail view in vertical section of a heel-holder and its surrounding parts; Fig. 6 is a detail view in vertical section illustrating the mechanism for adjusting the pressure-plate; Fig. 7 is a view, partly in vertical section, showing the work-support and the nail-

transferrer; and Fig. 8 is a view in side elevation, partly in section, of a heel-holder and parts adjacent thereto.

The drawings illustrate the present invention applied to a machine of the type 70 shown in Letters Patent of Great Britain No. 5084 of 1903 to Bates *et al.* As will be evident from the nature of the invention, it is also applicable to other types of heel-attaching or heel-loading machines. 75

The machine shown in the present drawings includes, as in the prior patent above mentioned, a work-support 1 upon which the boot or shoe to be heeled is placed and an oppositely disposed pressing member 32. 80 The upper end of the work-support is provided with a die-block 2 having driver passages, and drivers carried by a driver bar 3 are arranged in these passages and are automatically actuated to drive nails 85 through the sole of a shoe into a heel in the manner described in said patent. The work-support is arranged to slide in a horizontal guideway 4 carried by a vertically reciprocating member 6. The work-support is moved by the operator from the position indicated by dotted lines in Fig. 1 into that shown in full lines in said figure to place a shoe in attaching position.

According to the present invention a nail-transferrer 8 is employed to supply nails to the die-block 2 and as shown is arranged to convey nails from a nail-assorting and delivering mechanism 10 of any suitable construction to said die-block. The transferrer 100 8 is splined upon a vertical spindle 12 rotatably mounted in bearings 14 upon the frame, said spindle having a handle 16 by means of which the transferrer may be reciprocated by the operator. In the movement of the transferrer 8 into nail-receiving position it is raised by means of a spiral cam surface 18 on the block 20 mounted upon the frame co-operating with a runner 22 upon the transferrer arranged 105 to engage said cam surface. A spring 24 (see Fig. 2) tends to keep the runner 22 in engagement with the cam surface 18. The block 20 is preferably adjustably secured to the machine frame so that the position of the cam surface 18 may be varied to raise or lower the path of movement of the transferrer. A convenient construction 110 comprises a nut 26 screwed upon the spindle 12 and engaging the lower face of the hub of the handle 16, said handle being splined upon the spindle 12, and the upper face of said hub engaging the block 20. The block 20 is secured to the machine frame by a rib and groove connection or any convenient construction permitting it to be adjusted in a vertical direction by the nut 26 and preventing its rotation.

A heel carrier 28 is provided with a stud 30 rotatably mounted in a bearing 31 formed 120 125

upon a slide 32 (see Figs. 3, 4 and 8). The slide 32 is sustained upon a foot 34, said foot being formed upon a curved slide 36 hereinafter referred to. The slide 32 is coupled to the transferrer 8 so as to move therewith. The construction shown includes a link 38 attached at one end by a universal joint 40 to the slide 32 and at the other end by a universal joint 42 to one arm of an elbow lever 44, said elbow lever being pivoted on an arm 46 (see Fig. 2) secured to a post 48 hereinafter referred to. A frame 50 is secured to the upper end of the spindle 12, said frame sustaining a vertical rod 52. A link 54 arranged to move freely upon the rod 52 is pivotally connected with the other arm of the elbow lever 44. As will be obvious the connections between the transferrer and the slide 32 permit the slide 32 to be adjusted vertically or swung about a horizontal axis if desired.

The heel carrier 28 is provided with a three-armed lever 56 (see Fig. 4) rigidly secured to the stud 30. Each arm of the lever is provided with a roller 57 at its end which, as the slide 32 is moved to and fro by the transferrer 8, is engaged in turn by two cam surfaces, one 58 formed on a plate 60 (see Fig. 3) secured to the curved slide 36, and the other 62 being formed on a plate or member 64 pivoted to the curved slide. On the movement of the nail-transferrer into nail-delivering position, the roller upon one of the arms of lever 56 is engaged by the cam surface 62 and the carrier 28 is partially rotated to bring the roller into the position shown in Fig. 3. In the construction illustrated, this partial rotation amounts to about 75°. In the movement of the nail-transferrer into nail-receiving position the cam surface 58 is engaged by the roller shown in Fig. 3 and rotates the carrier 28 substantially 45° farther to bring a heel-holder thereon into alignment with the post 48. The plate or member 64 carrying the cam surface 62 engages a stop 66 on the curved slide 36 and is held from movement in the reverse direction by a spring, not shown, which permits a roller to pass by said plate 64 in the movement of the nail-transferrer into receiving position. The cam surface 58 terminates at its forward end in a recess arranged to receive one of the rollers 57 on the movement of the corresponding holder into operative relation with the driving mechanism, thus locking the carrier against angular movement until the slide 32 is moved rearwardly after the operation of the drivers.

Each heel-holder as illustrated comprises a back gage 68 having a V-shaped recess to receive the curved end of a heel and arranged to slide in guideways upon the carrier 28, and a breast gage formed as a

straight bar 70 for engaging the breast of the heel. Each breast gage is carried by a plate 72 arranged to slide in guideways toward and from the back gage and is yielding held toward the back gage by a spring 74. The plates 72 bear against the tread surfaces of the heel blanks and serve to position them properly for presentation to the upper pressing member 32. To permit all the back gages 68 to be adjusted simultaneously, rack bars 76 are formed upon them and are arranged to mesh with a pinion 78 rotatably mounted on the stud 30. Integrally with the pinion 78 is formed a beveled gear 80 (see Fig. 5) meshing with a second beveled gear 82 mounted on the shaft 84 journaled in the slide 32 and arranged to be actuated by the operator. During the rotation of the carrier 28 in the operation of the machine, the shaft 84 will be turned idly by the gear 80 which rotates with the carrier, there being sufficient frictional resistance to movement of the back gages on their support to prevent them from being moved relatively thereto in the rotation of the carrier 28. Each breast gage 70 when no heel is in the corresponding heel-holder is held by its spring 74 in engagement with a wedge-shaped block 85, a projection 83 upon said breast gage coming in contact with said block. The wedge-shaped block 85 is carried by the adjacent back gage 68 so that as the back gages are adjusted by the operator toward or from the center of the carrier 28, the breast gages are adjusted in the reverse direction. As will be obvious this construction permits heels of different sizes to be conveniently inserted in the holders and to be retained upon the holders with their centers in substantially the same position.

The post 48 is mounted for vertical adjustment in the head of the machine and is held from rotary motion therein, a hand wheel 86 being provided to facilitate its adjustment. The curved slide 36 is mounted in guideways 88 formed upon the lower end of the post 48 and said slide is provided with means for adjusting it in said guideway, a convenient construction including a worm 90 carried by a spindle 92 journaled in the post 48, said worm engaging worm teeth formed upon the curved slide 36. By adjusting the slide 36 in its guideway the carrier 28 may be sustained in an inclined position so that a heel against which the heel seat of a shoe is pressed may be held in an inclined position and the nails consequently driven in an oblique relation to the lifts of the heel. As shown in Figs. 1, 5, 8, and 125, the machine is adjusted for inserting nails at an inclination to the tread face of the heel. The guideway 88 is preferably curved in the arc of a circle, having a center at or near the level of the heel seat (see 130

Fig. 8) so that the pressure-plate formed by the slide 36 coöperating with the breast gages with which the tread face of the heel come in contact is adjustable about an axis 5 that is approximately at the level of the heel seat. The post 48 is slotted at 94 (see Fig. 4) and a clamping bolt 96 actuated by a handle 97 is provided to coöperate with said slotted post to hold the curved slide 36 10 in adjusted position.

The nails are delivered to the die-block 2 with said die-block in its outer position shown in Fig. 3. To insure that the die-block shall be in proper position for the reception of the nails, the machine shown includes means for adjusting it into correct position in the movement of the nail-transferrer into nail-delivering position. This is shown as a lever comprising arms 98 and 15 99, said lever being pivoted upon the frame at 100 and actuated by the transferrer 8 by means of a link 102 connected to arm 99 and an eccentric 104, for actuating said link said eccentric being secured to the spindle 20 12. A lug 106 is formed on the work-support for engagement with the arm 98 so that when the transferrer 8 is moved into nail-delivering position, as shown in Fig. 3, said arm 98 will move the die-block outwardly in case it is not in its outermost position, a suitable stop device, not herein shown, being provided if desired to limit outward movement of the die-block. 25 30

In the operation of the machine above described, the work support being in its outer position, the nail-transferrer carrying a gang of nails is moved by the operator's attendant into nail-delivering position above the die-block. In its movement it adjusts mechanically the die-block into proper position to cause its nail cavities to be in line with the nail passages of the transferrer when the latter is in position above the die-block, and also moves a heel-holder 40 45 in which a heel has been previously inserted by the attendant part way toward attaching position. The nail-transferrer is brought into close relation to the face of the die block by the spring 24, which yieldingly depresses said transferrer in its movement. The transferrer after delivering its nails to the die-block is returned by the attendant to receiving position. In its return movement it is raised by the cam 18, 50 55 so that in receiving position it is in close relation to the nail-supplying mechanism. Also in its return movement, it completes the movement of a heel-holder into attaching position. A shoe may then be placed 60 65 upon the work-support by the operator, the work-support moved into attaching position and the machine started which thereupon automatically lifts the jack to place the work under pressure, as in the machine of the prior patent above mentioned, and

drives the nails from within the shoe into the heel. After the operation of the drivers the jack descends and the heel which has been attached to the shoe is drawn downwardly out of its holder. While a shoe is 70 being heeled, the attendant may insert a heel for the next shoe in the holder next to that in attaching position. It will be evident that a greater or less number of heel-holders than three may be employed. 75 Where three are used the holders may be conveniently reached from the side of the machine, as will be apparent from Fig. 4.

When a change is made in the size of the heels being attached adjustment of the 80 gages is desirable. It will be seen that in properly adjusting the gages upon one holder to fit a heel, the gages upon the remaining holders are simultaneously adjusted to the same extent, and separate adjustment of the gages upon the different holders is thereby rendered unnecessary. In case adjustment in inclination of the pressure-plate is desired, it may be secured by 85 adjusting the curved slide 36 in its guideway, since the carrier 28 for the heel-holders is supported by the slide 36. It will be seen that in adjusting the latter, adjustment of the former to the same degree of inclination is secured. The adjustment of the slide 36 90 is about an axis located at or near the heel seat of the shoe as shown in Fig. 8, and it will be noted that this feature is advantageous in that the heel may be adjusted in inclination without displacing its heel seat 100 face longitudinally of the shoe.

As will be apparent from the above description, modifications in the machine herein disclosed could be made without departing from the present invention. For example, the machine shown could be adapted, if desired, to secure successively to a shoe a heel blank and a top lift. It may also be observed that the term nails herein employed is intended to include slugs or other 110 equivalent devices.

Having described my invention what I claim as new and desire to secure by Letters Patent of the United States is:—

1. A machine for inserting nails in heels, 115 having, in combination, a die block and drivers working in said block, a plurality of heel-holders arranged for movement into and out of operative relation to said die block, a nail-transferrer for supplying nails 120 to said die block arranged for a reciprocatory movement between a nail-receiving position and a nail-delivering position, and means for moving said holders successively into operative position arranged to be 125 brought into operation by successive reciprocations of said nail-transferrer.

2. A machine for inserting nails, having, in combination, a die-block provided with nail passages and a nail-transferrer for 130

- supplying nails to said die-block, arranged for movement laterally of the die-block from a nail-receiving position into a nail-delivering position above the die-block, and means for yieldingly depressing said transerrer in its movement between said positions whereby it is brought into close relation to the upper face of the die-block. 5 70
3. A machine for inserting nails in heels, having, in combination, a die-block arranged for movement into and out of operative position and provided with nail-receiving passages, a nail-transferrer for supplying nails to the die-block arranged for movement from a nail-receiving position at one side of the die-block into a nail-delivering position above the die-block, and means arranged to be brought into operation in the movement of the nail-transferrer into delivering position for adjusting the die-block into a predetermined position. 10 75
4. A machine for inserting nails in heels, having, in combination, a die block and drivers working in said block, a plurality of heel-holders arranged to be brought successively into operative relation to said die block, gages carried by the holders for retaining heels in position upon the holders, and means for adjusting simultaneously the gages upon the several holders. 15 80
5. A machine for inserting nails in heels, having, in combination, a die block and drivers working in said block, a heel-holder, arranged for movement into and out of operative relation to said die block, a nail-transferrer arranged for movement between a nail-receiving position and a nail-delivering position, means arranged to become effective in the movement of the transerrer into delivering position, for imparting to said holder a preliminary movement toward operative position, and means arranged to become effective in the reverse movement of the transerrer for completing the movement of the holder into operative position. 20 85
6. A machine for inserting nails in heels, having, in combination, a die block and drivers working in said block, a rotatable heel carrier provided with a plurality of heel-holders and arranged for a reciprocatory movement with relation to said die block, a nail-transferrer for supplying nails to said die block arranged for movement between a nail-receiving position and a nail-delivering position, and means arranged to become effective in the movement of said transerrer for imparting to said carrier simultaneous rotatory and translatory movements to bring successive heel-holders into operative relation to said die block. 25 90
7. A machine for inserting nails in heels, having in combination, a plurality of holders for heels, a plurality of sets of gages for positioning the heels upon the holders ar- 30 95
- ranged for adjustment to accommodate heels of different sizes, and means providing connection between the several sets of gages whereby they may be adjusted simultaneously. 35 100
8. A machine for attaching heels, having, in combination, a shoe support arranged for movement into and out of heel attaching position provided with nail receiving passages and drivers working in said passages, and a movable nail transerrer for supplying nails to the passages of the shoe support while said shoe support is out of heel attaching position. 40 105
9. A machine for attaching heels, having, in combination, a shoe support arranged to be moved manually into and out of heel attaching position having nail receiving passages and drivers working in said passages, a movable nail transerrer for supplying nails to the passages of the shoe support while said support is out of attaching position, and means for adjusting the support into a predetermined position for receiving nails from said transerrer. 45 110
10. A machine for inserting nails in heels, having, in combination, a die block and drivers working in said die block, a rotatable heel carrier provided with a plurality of heel holders and arranged for reciprocatory movement with relation to said die block, means for reciprocating said carrier and means for imparting to the heel carrier a rotary movement in its reciprocation to bring successive heel holders into operative relation with said die block. 50 115
11. A machine for inserting nails in heels, having in combination, a work-support, nail driving mechanism, a rotatable carrier having radially disposed holders, and mechanism for imparting to said carrier intermittent rotations of unequal extent. 55 120
12. A machine for inserting nails in heels, having in combination, a work-support, nail driving mechanism, a rotatable carrier having radially disposed holders, and mechanism for imparting to said carrier angular movement of alternately greater and lesser extent. 60 125
13. A machine for operating on heels having, in combination, coöperating oppositely disposed members for exerting pressure on a heel blank, a three-arm carrier having a similar blank holder on each arm and being mounted for step-by-step rotation to bring successive blanks into alinement with and between said members, a support for said carrier constructed to be moved vertically, a horizontally reciprocatory slide, and means for effecting a step-by-step rotation of said carrier by the reciprocation of said slide whereby a new heel blank is brought into operative position at each operation of the machine. 65 130
14. A machine for operating on heels hav-

ing, in combination, coöperating oppositely disposed members relatively movable for exerting pressure on a heel blank, a three-arm carrier having similar blank holders on each arm and being mounted for step-by-step rotation in one direction to bring successive blanks between said members, a support for said carrier constructed to be moved vertically, a horizontally reciprocatory slide, and means for effecting a step-by-step rotatory movement to said carrier by the reciprocation of said slide and actuating means for the slide, said actuating means having operative connection with the slide in all vertical positions of the carrier and its support.

15. A machine for inserting nails in heels, having in combination, a work support, nail driving mechanism, a rotatable carrier having radially disposed holders arranged substantially 120° apart, and means for rotating said carrier for substantially 120° in separate movements between successive actuations of the nail driving mechanism.

16. A machine for inserting nails in heels, having, in combination, relatively movable work-engaging members arranged to hold a heel under pressure, nail-driving mechanism and actuating mechanism therefor arranged for operation independently of said work-engaging members, a carrier mounted for turning movement and having radially disposed heel-holders arranged substantially 120° apart, means for turning said carrier between successive actuations of the driving mechanism to move a holder substantially 120° from its heel-receiving position to an intermediate position, and then substantially 120° farther in the same direction to present a heel in alignment 40 with the driving mechanism, and locking means for the carrier.

17. A machine for inserting nails in heels, having, in combination, a normally stationary member and a coöperating member mounted below said stationary member and movable toward the latter to subject a heel to pressure, nail-driving mechanism arranged for operation while a heel is held under pressure, a rigidly supported carrier 50 mounted for turning movement and having holders constructed and arranged to present a plurality of heels with their tread surfaces parallel with the plane of the effective face of said stationary heel-engaging member, and means for turning said carrier to present successive heels laterally to said pressing members.

18. A machine for inserting nails in heels, having, in combination, a normally stationary member having an acting face, a relatively movable member mounted below said normally stationary member and being movable toward and from the latter to subject a heel to pressure, a rigidly supported carrier mounted for movement about an

axis adjacent to said stationary member and having a plurality of radially disposed heel-holders arranged to maintain a plurality of heels with their tread faces parallel with the plane of the face of the stationary member, means for turning said carrier to present successive heels laterally to said pressing members between successive actuations thereof, locking means for the carrier, nail-inserting devices, and means for actuating said devices while a heel is held under pressure.

19. In a machine of the class described, the combination with work-supporting means, of nail-driving mechanism, a rigidly supported rotatable carrier having a plurality of heel-holders, a plate arranged to overlie the tread surface of a heel presented to each holder, said holders being constructed and arranged to leave the heel seat surface of the heel exposed, mechanism for rotating said carrier to present successive heels laterally to said work-supporting means, locking means therefor, and means for actuating the driving mechanism while a heel is engaged by the work-supporting means.

20. In a machine of the class described, the combination with nail-drivers, of mechanism for reciprocating said drivers, a rotatable three-arm blank-carrier, supporting means therefor constructed and arranged to maintain said carrier in a plane oblique to the path of said drivers, and means for rotating said carrier between successive actuations of the drivers to present blanks successively to the nail-drivers.

21. In a machine of the class described, the combination with heel-pressing members, of nail-drivers associated therewith and arranged to reciprocate through one of said members, a rotatable heel-carrier having radially disposed heel-holders, supporting means for said carrier constructed and arranged to maintain said carrier in a plane oblique to the path of the drivers, and means for rotating said carrier between successive actuations of the drivers to present heels one by one to said pressing members.

22. In a machine of the class described, the combination with oppositely disposed work-pressing members, of reciprocatory drivers, a rotatably mounted heel-carrier arranged to support a plurality of heels with their tread faces in a common plane, a plate for determining said plane, supporting means for the carrier constructed and arranged to maintain said carrier in a plane oblique to the path of said drivers, means for rotating said carrier between successive actuations of the drivers to present heels to the work-pressing members, means for locking said carrier with a heel held in position to receive pressure from said members, and actuating means for the drivers arranged for

operation while a heel is maintained under pressure.

23. In a heel nailing machine, the combination with a rotatably mounted blank carrier, of actuating mechanism therefor, and nailing means, said carrier being mounted for angular adjustment relative to the nailing means and having at all times operative connection with its actuating mechanism regardless of its angular position.

24. In a machine of the class described, the combination with nail-driving mechanism, of a carrier mounted for turning movement, having radially arranged heel-holders and being disposed in operative relation to said nail-driving mechanism, a shaft on which said carrier is rigidly mounted, a member fast on said shaft having projections corresponding in number with the number of heel-holders, and a pivoted spring-pressed member arranged to engage said projections for effecting a predetermined turning movement of said carrier.

25. In a heel nailing machine, the combination with nail-driving mechanism, of pressing means constructed and arranged to hold a heel under pressure during the operation of the nail-driving mechanism, a rotary heel-carrier for presenting heels between said heel-pressing means, actuating means for said carrier, a reciprocatory slide interposed between said actuating means and said carrier and coöperating mechanism including a pivoted member arranged to cause a limited angular movement of said carrier on the reciprocation of the slide.

26. In a machine of the class described, the combination with work-engaging members, one of which comprises a nail-block, drivers working therein, actuating means for said drivers, a nail-carrier mounted for movement to and from the nail-box, a three-arm heel-carrier mounted for turning movement and having radially disposed heel-carriers, means for moving said nail-carrier to deliver nails to said nail-block and also to effect turning movement of the heel-carrier to present a heel to said work-engaging members, said means being arranged for operation between successive actuations of the drivers, and means for locking the carrier with a heel in position between the work-engaging members.

27. A machine of the class described having, in combination, relatively movable work-engaging members arranged to hold a heel blank under pressure, nail driving

mechanism, a three-arm carrier mounted for turning movement and having a heel blank holder on each arm, means for positioning the blanks with their tread surfaces in a common plane, said carrier being so constructed and arranged that when one holder presents a heel blank in position to be clamped by the work-engaging members another will have brought a second heel into position in readiness to replace the clamped heel and the third holder will be in receiving position, together with means for turning said carrier always in the same direction to present successive heel blanks to the work-engaging members, and simultaneously to move successive holders into receiving position.

28. A machine of the class described, having, in combination, relatively movable work-engaging members, driving mechanism associated therewith, a rotatable carrier having three radially disposed heel blank holders, said carrier being constructed and arranged to present successive blanks to the work-engaging members by intermittent rotation in one direction and to receive a blank when one of the holders is in a position substantially 240° from the driving mechanism, means for rotating said carrier to move successive holders from receiving position to driving position, and means for engaging the tread surfaces of the heel blanks to position them in a common plane, each blank holder being constructed and arranged to engage frictionally the edges of a blank thereby permitting its removal from the holder by a movement at right angles to its tread face after the operation of the driving mechanism and before further rotation of the carrier.

29. In a machine of the class described, the combination with a nail block, of a nail transperrer mounted for movement to and from said nail block, driving mechanism and a rotatable blank carrier, said carrier being rotated in one direction for presenting successive blanks to said driving mechanism by the movement of said nail transperrer in opposite directions.

In testimony whereof I have signed my name to this specification in the presence of two subscribing witnesses.

JOSEPH GOULDBOURN.
